SODIUM SILICATE DETERGENT

Foster Dee Snell, Brooklyn, N. Y., and Henry V. Moss, St. Louis, Mo., assignors to Swann Research, Inc., a corporation of Alabama

No Drawing. Application April 10, 1931,
Serial No. 529,284

8 Claims. (Cl. 87—5)

This invention relates to sodium silicate detergents and in particular to detergents containing high alkali ratio sodium silicates.

One object of this invention is to provide a 5 detergent which is entirely water soluble and has improved emulsifying properties.

Another object is to provide a sodium silicate detergent which has water softening properties.

Still another object of this invention is to 10 provide a detergent which when dissolved in water will provide a higher hydroxyl ion concentration and at the same time a lower interfacial tension than other buffered alkaline salts in like concentration. The term "buffered alkaline salts" as ordinarily understood refers to those salts which 15 in solution do not deliver their full alkalinity at once. However, as the alkalinity of solutions of such salts is used up, either by neutralization or saponification, these salts have the property 20 of liberating additional alkalinity, thus maintaining a uniform hydroxyl ion concentration.

We have now discovered that alkali silicates can be produced having a higher ratio of alkali to silica than that contained in alkali meta silicate and that such high alkali ratio silicates in solution yield a higher concentration of hydroxyl ions, a lower interfacial tension, and possess greater detergent power than alkali silicates of lower alkali ratio. In fact, we have found our 25 new detergent to possess greater detergent power than any buffered alkaline salt which we have thus far examined.

Our new detergent may be produced in the following manner:—

35 Take 670 pounds of sodium metasilicate of the composition represented by the formula $Na_2SiO_3 \cdot 6H_2O$ and which has been ground to pass through a 20 mesh screen and mix it with 180 pounds of caustic soda of 76% Na_2O content, 40 which has been ground to the same fineness. The metasilicate may vary in its content of water of hydration above and below the hexahydrate above mentioned in which case the amount of caustic added to a given quantity of hydrate is such as 45 to give a ratio of $Na_2O:SiO_2$ in the final silicate of 5 to 3. Mixing of these components is preferably done in a power mixer provided with a water jacket and furnished with an efficient agitating device.

50 During the mixing of these ingredients, heat is developed, the temperature rising to above 40° C. and being maintained at preferably less than 60° C. by means of cold water circulating through the jacket. As the ingredients become 55 mixed, a chemical reaction takes place, forming

a compound of sodium silicate wherein the proportion of Na_2O to SiO_2 is that employed in the mix, and the powdery mass becomes plastic. On continued stirring granular particles form in the plastic mass, the particles growing as the stirring continues and becoming gradually more dry and less plastic. At the same time the particles become rounded by the continued rolling and rubbing together, and gradually become larger as the plasticity of the mass decreases and ag- 10 glomeration proceeds.

The entire mass thus becomes gradually less plastic in character and the charge may be removed from the mixer as a mass of small more or less spherical granules still, however, somewhat plastic. If the product is to be used as such, we have found it desirable to spray the granules with approximately 0.1% of oleic acid to lower the hygroscopic character of the substance. This particular fatty acid or any other suitable 20 saponifiable fats, such as stearic or palmitic acid, is added by means of a spraying device before the product is discharged from the mixer.

In addition to using the sodium silicate alone, we have found that the addition of soda ash and 25 trisodium phosphate aid in the keeping and free flowing qualities of the product. It has also been observed that the addition of finely divided soda ash and anhydrous trisodium phosphate to the granular mass in the mixer prevents further 30 growth of the particles already formed during subsequent mixing or handling. Accordingly, we prefer to add to the above mentioned quantities while still in the mixer, 100 pounds of fine soda ash and 50 pounds of anhydrous trisodium phosphate. This addition is preferably made after 35 spraying with the oleic acid or other saponifiable oil, which in this case is added to the mass in the manner described above.

After all the ingredients have been added as 40 above described, the product is discharged from the mixer and is allowed to age for a period, say, 24 hours, in covered containers during which time the chemical reactions taking place are given an opportunity of proceeding to comple- 45 tion. After the ageing period has been concluded,—which ageing period is desirable for these silicates, whether or not the soda ash and trisodium phosphate has been added to the sodium silicate,—the granules are somewhat ag- 50 glomerated or lightly caked together. These are now broken up by grinding or otherwise, and the product screened and placed in containers.

While, of course, any excess of Na_2O over that present in metasilicate may be used, we prefer 55

to work with a ratio of Na_2O to SiO_2 greater than that of sodium metasilicate in which the ratio is 1 to 1, and have in fact used a ratio up to and including 2 to 1. A particularly desirable ratio 5 we have found to be 1.666 to 1, or 5 Na_2O to 3 SiO_2 .

When working with ratios between the limits of 1.600 to 1 and 1.750 to 1, expressed as mols of Na_2O to SiO_2 , we have observed that the agglomeration of the mass with formation of granules 10 of lower plasticity follows the more highly plastic stage in a noticeable manner. We believe this phenomena to be due to certain chemical reactions taking place with the formation of new compounds. These reactions apparently take 15 place throughout the entire range of concentrations herein specified—they being particularly noticeable when working within the ratio of 1.6-1.75 mols Na_2O to 1 SiO_2 .

While we have described our process in this 20 specification as being carried out using sodium metasilicate and caustic soda as starting material, a silicate having a lower alkali to silica ratio than that existing in the metasilicate may also be employed. In a co-pending application, 25 Serial No. 463,758, filed June 25, 1930, now Patent No. 1,989,765, we have described and claimed a product consisting of sodium metasilicate, together with a process for making same, in which a low alkali ratio silicate is treated with caustic 30 to bring the molal ratio of Na_2O to SiO_2 in the compound to 1 to 1. A compound such as this latter may be employed as one of the starting materials in the present invention if desired. On the other hand, as we have pointed out above, if 35 a sodium silicate of the proper ratio is not available, it is possible to use a lower alkali ratio silicate and by adding an equivalent amount of caustic soda bring the final ratio to that herein specified.

40 As has already been pointed out, the use of hydrates or other forms of metasilicate other than the hexahydrate is contemplated by this invention. For example, we may use either the anhydrous salt, or the salt with 4, 5, 6, 9, or 14 molecules of water or mixtures of these as starting material, altho we prefer to start with either the penta or hexahydrated meta silicate, as giving a more desirable product.

Another valuable property of our new product 50 is that the high hydroxyl ion concentration developed in aqueous solutions of said product increases the detergent power of soap solutions, because of its effect on the interfacial tension and the increase in wetting power of its solutions. By virtue of the buffering effect of the 55 silica in our product we are enabled to obtain a solution containing the required amount of alkalinity for a washing operation without at any time exceeding the safe hydroxyl ion concentration. Solutions prepared from our product are 60 therefore especially valuable for laundering fine cotton fabrics and particularly as a soap builder in industrial laundry operations.

While we have described our invention in but 65 one form, it will be obvious to those skilled in the art that it is not so limited, but is susceptible of various changes and modifications, without departing from the spirit thereof, and we desire, therefore, that only such limitations shall be 70 placed thereupon as are imposed by the prior art or as are specifically set forth in the appended claims.

What we claim is:

75 1. A process of producing a detergent which consists in providing a finely ground sodium sili-

cate, adding finely ground caustic soda thereto until the ratio of alkali expressed as Na_2O , to silica expressed as SiO_2 is greater than 1 to 1 and not more than 2 to 1, mixing and stirring said finely ground ingredients to bring about a 5 reaction therebetween and form a mass of granular particles, protectively coating said granular particles by spraying with approximately 0.1% of a saponifiable oil, and cooling with disintegration to form a dry free flowing product. 10

2. A process of producing a detergent which consists in providing a finely ground sodium sili- 15 cate, adding finely ground caustic soda thereto until the ratio of alkali in the mixture expressed as Na_2O to silica expressed as SiO_2 is greater than 1 to 1 and not more than 2 to 1, stirring said finely ground ingredients until a mass of granular particles is formed, protectively coating said particles by spraying with approximately 20 0.1% of a saponifiable oil, adding finely ground soda ash and anhydrous trisodium phosphate thereto to approximately 15% of the weight of the mass to aid in the keeping and free flowing properties thereof, and ageing and cooling with 25 disintegration to form a dry granular free flowing product.

3. A granular detergent containing more than 30 50% of the reaction products of caustic soda and sodium silicate in which the ratio of alkali expressed as Na_2O to silica expressed as SiO_2 is approximately 5 to 3.

4. A granular detergent containing more than 35 50% of the reaction products of caustic soda and sodium silicate in which the ratio of alkali expressed as Na_2O to silica expressed as SiO_2 is approximately 5 to 3, and a lesser percentage of soda ash and trisodium phosphate intimately mixed with said reaction product. 40

5. A granular detergent containing more than 45 50% of the reaction products of caustic soda and sodium silicate in which the ratio of alkali expressed as Na_2O to silica expressed as SiO_2 is approximately 5 to 3, and a lesser percentage of soda ash and trisodium phosphate intimately mixed with said reaction product and coated with approximately 0.1% of a saponifiable oil. 45

6. A detergent comprising irregular granular to spherical particles containing as a principal 50 ingredient the reaction product of caustic soda and sodium silicate in which the ratio of alkali expressed as Na_2O to silica expressed as SiO_2 is greater than 1 to 1 and not more than 2 to 1. 55

7. A detergent comprising irregular granular to spherical particles containing as a principal 60 ingredient the reaction product of caustic soda and sodium silicate in which the ratio of alkali expressed as Na_2O to silica expressed as SiO_2 is greater than 1 to 1 and not more than 2 to 1, said detergent having incorporated therein a minor proportion of soda ash and trisodium phosphate. 65

8. A detergent comprising irregular granular to spherical particles containing as a principal 70 ingredient the reaction product of caustic soda and sodium silicate in which the ratio of alkali expressed as Na_2O to silica expressed as SiO_2 is greater than 1 to 1 and not more than 2 to 1, said detergent having incorporated therein a minor proportion of soda ash and trisodium phosphate and coated with approximately 0.1% of a saponifiable oil. 75
